UNITED STATES PATENT OFFICE.

HENRY LYLE MCGOWAN, OF ST. JOHN, CANADA.

SIGNALING-MACHINE.

SPECIFICATION forming part of Letters Patent No. 708,904, dated September 9, 1902.

Application filed January 23, 1902. Serial No. 90,996. (No model.)

To all whom it may concern:

Be it known that I, HENRY LYLE MCGOWAN, painter, a subject of the King of Great Britain and Ireland, residing at the city of St. John, in the county of St. John and Province of New Brunswick, Canada, have invented a new and useful Signaling-Machine, of which the following is a specification.

My invention relates to improvements in machines in which water-power is used to operate a signal or furnish a motive power; and the objects of my invention are, first, to utilize the ebb and flow of tidal water for the purpose aforesaid; secondly, to utilize a head of water from a constant source of supply for the same purposes, and generally to furnish a subaqueous water-motor. I attain these objects by the mechanism illustrated in the accompanying drawings, in which—

Figure 1 is a vertical section of a machine embodying the application of my invention as a fog-signal. Fig. 2 is a vertical section of the regulating-cock. Fig. 3 is a detail view of the valve S, illustrating its operation.

Similar letters refer to similar parts throughout the several views.

The tower e e', standing on a ledge in a tidal water, may be of stone, wood, iron, or other durable material. It consists of two parts. The lower part e, having compartments i and j, serves as a foundation for the upper part e', which is preferably an iron framework to carry the signal-gong. It is obvious that the walls of the lower part of the tower and, in fact, the whole structure must be thoroughly and strongly built and ballasted to stand the stress of storm and sea, and in a cold climate the walls should be thick enough to protect the water in the pipes and tanks from freezing.

The compartment i is a waterproof tank or reservoir, preferably of iron. It should be capable of holding such a quantity of water that the fall thereof, adjusted by the regulating-cock q r, into the tip-tank m will operate, by means of the rod f and arm f', the striker x of the gong t for, say, twelve hours, or between high tides each day. The reservoir i is supplied from the tidal water surrounding the tower by the pipe o through the openings a a' a''. The opening a'', admitting the tide to the pipe o, is provided with a grating to act as a screen and exclude fish,

dirt, &c., from the pipe o. The opening a' is provided with the check-valve b, which prevents the outflow of water from the reservoir i. When the water in the reservoir has risen to the desired level so as to float the ball S, the ball-cock s, which is the ordinary form of ball-cock used in water-closet tanks, becomes operative and closes the openings a and a'. The air in the reservoir escapes as the water flows in through the vent-pipe h. This pipe should extend far enough above high water to prevent the waves from flowing into it. The reservoir i may be entered for the purpose of cleaning, repairing, &c., through the manhole l, which should have a water-tight cover.

The compartment j, for convenience placed below the reservoir i, serves as a waste-tank and may be used, as in drawings, as a compartment for the tip-tank m or other motor employed to operate the signal apparatus. It is emptied by means of the pipe p, having check-valve c to prevent the reflow of the tide into compartment j, and the outlet d, provided with a grating to act as a screen to exclude fish, dirt, &c., from the pipe. The manhole l, having water-tight cover, affords access to the waste-tank j. The regulating-cock q r has the handle q and slot or gate r. It is for the purpose of adjusting the flow of water from the reservoir to the tip-tank m in relation to the interval of the strokes desired on the signal-gong t. If the tip-tank m or other motor is placed in the waste-tank j, as shown in the drawings, the waste-tank should be of such a depth that the level of the water in it will be always below the tip-tank or motor. The tip-tank or other motor used may, if so desired, be placed in a compartment between the reservoir and waste-tank, necessary and obvious mechanical changes being made. The waste-tank j is ventilated by the vent-pipe y, which serves as a shield for the rod f and should extend far enough above high water to prevent the waves overflowing into it.

The tip-tank m is pivoted on a bar n, set into the walls of waste-tank j. It is connected by pivot-joints g with rod f, which rod f is connected at pivot-joint g' with the arm f'. When the tip-tank m is at rest, the arm f' engages with the striker x, as indicated in the drawings. When the tip-tank fills and tips,

as indicated by the dotted lines, it raises the rod *f* and arm *f'*, and thereby the striker *x*, as indicated by dotted lines, until the arm *f'* is disengaged from the striker *x* by a trip suitably placed on the frame *e'*, when striker *x* drops heavily on the gong *t*, giving the required signal. The spring *u* is to hold off the striker from the gong when at rest. The gong *t* is attached to the frame *e'* by the yoke *v*, having arm *w*, to which is pivoted or hung the striker *x*.

In the drawings I have shown a signal-tower built on a ledge of rock covered at low tide (indicated by line *z z*) to such a depth that 15 the pipes *o p* may have their outward openings below low-water mark. This is not essential, but is advantageous where practicable to avoid injury to the gratings from things drifting on the water and to guard 20 against the icing up of the gratings. The walled part of the tower is below high-water mark to avoid as much as may be the force of heavy seas. The pipe *o* may be carried through the waste-tank *j* and into the reservoir *i* instead of through the wall, as shown. 25 They should be placed where they will be readily accessible and best guarded against the danger of frost. The waste-tank *j* should be above the level of low-water mark, so as 30 to insure its being emptied when the tide falls.

The mode of working my invention is as follows: The machine having been built as described and the regulating-cock *q r* adjusted by means of the handle *q*, so as to admit through slot *r* the desired flow of water to the tip-tank *n*, admit the tidal water through supply-pipe *o* into reservoir *i*, and as it flows into tip-tank *m* it furnishes the head of force required for operating the gong *t* in the manner described and continues to do so. As the tide rises the level of the water in the reservoir rises until the openings *a a'* are closed by the ball-cock *s*, when a head of water will have been accumulated in the reservoir more than 45 is required for working the signaling apparatus during the ebb of the tide and until the next tide begins to flow into the reservoir. As the used water flows out of the tip-tank *m* it accumulates in the waste-tank *j* until 50 the level of the ebbing tide is below the waste-tank *j*, when the pressure of the water in waste-tank *j* opens the gate of valve *c* and allows the discharge of such waste water from the tower. When the waste-tank is 55 emptied, the gravity of the valve-gate closes valve *c* and aided by the pressure of the tide as it rises again prevents the reflow of the tidal water into tank *j*, and so from tide to tide the head of water supplied by one tide 60 continues to operate the signaling apparatus not only while the tide is rising and at high water, but also while it ebbs and until each succeeding tide flows into the reservoir. The signals are thus automatically and constantly

given at the regular intervals for which the apparatus is adjusted.

It will be seen that where fog-signals are required at a place where the rise and fall of tide are too little to furnish the required head of water in the reservoir *i* a head of water 70 may be induced into the reservoir by a supply-pipe from any constant source of water-supply available, and the head of water so supplied will operate the signal apparatus in the same manner as the supply of tidal water 75 above described. While in the drawings I show the application of my invention as a fog-signal, it is readily seen that the force of the water flowing from reservoir *i* into the vacuum-tank *j* can be utilized by appropriate machinery for any purpose within the capacity 80 of the head of water supplied.

It is well known that bell-buoys often drift out of place, are sometimes drawn under water and sometimes overturned, that in smooth 85 water they do not give their signals, and in any case give their signals at irregular intervals. My invention furnishes a fog-signal free from these drawbacks from usefulness.

For clearness in the drawings the level of 90 the water in the reservoir is represented below the height it would attain to at high water, when of course the level of the water in the reservoir would be at opening *a* and the openings *a a'* would be closed by the ball-cock 95 *s*, as described.

I claim as new—

1. In a signal-tower for a tidal water the combination of a reservoir, having a supply-pipe for admitting thereto a head of the tidal 100 water, devices for shutting off such tidal water, an air-vent, a regulating-cock to secure an adjusted flow of the water from the reservoir into a tip-tank as described, devices for operating a signal-gong by the tipping of said 105 tip-tank, a waste-tank for receiving the used water from the tip-tank, and devices for discharging such water from the tower and for preventing the tidal water from flowing back into the waste-tank substantially as and for 110 the purposes described.

2. In a signal-tower the combination of a reservoir having devices for supplying the same with a constant head of water, as described, a regulating-cock to secure an adjusted flow of said water in the reservoir into a tip-tank as described, devices for operating by the tipping of said tip-tank a signal-gong, and devices for discharging from the tower the used water of the tip-tank, substantially 120 as and for the purposes described.

In testimony whereof I have signed my name to this specification in the presence of two subscribing witnesses.

HENRY LYLE McGOWAN.
